[57] CLAIM

The ornamental design for a vice, as shown and described.

DESCRIPTION

FIG. 1 is a front perspective view of a vice showing my new design;

FIG. 2 is a rear perspective view thereof;

FIG. 3 is a top plan view thereof, shown on an enlarged scale;

FIG. 4 is a side elevational view thereof, shown on a scale greater than FIGS. 1-3;

FIG. 5 is a front elevational view thereof, shown on the same scale as FIG. 4; and

FIG. 6 is a rear elevational view thereof, shown on the same scale as FIG. 4.

The bottom view of the vice is substantially flat and plain except for the central groove extending along the longitudinal axis.
